LOCK

Edward N. Jacobi, Milwaukee, Wis., assignor to
Briggs & Stratton Corporation, Milwaukee,
Wis., a corporation of Delaware

Application June 9, 1933, Serial No. 674,993

9 Claims. (Cl. 70—46)

This invention relates to certain new and useful improvements in key operable tumbler locks and has as an object to provide a novel dust cover to close the open end of the key-way.

5 A further object of this invention is to provide means for releasably holding a dust cover in open or closed position.

Another object of this invention is to provide a 10 dust cover for locks of the character described, wherein a common element provides both a hinge mounting for the cover and spring tension to hold the same in either open or closed position.

And a still further object of this invention is 15 to provide a dust cover for locks of the character described, which is an improvement and a simplification over other structures heretofore proposed and which may be readily assembled with the lock.

With the above and other objects in view which 20 will appear as the description proceeds, my invention resides in the novel construction, combination and arrangement of parts substantially as hereinafter described, and more particularly defined by the appended claims, it being understood 25 that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a side elevation of a lock with parts 25 broken away and in section and illustrating the dust cover of this invention applied thereto;

Figure 2 is a front view of the lock with parts of the cover and its mounting means broken away; and

Figure 3 is a perspective view of the cover and its mounting means shown disassembled and separate from the lock.

Referring now more particularly to the accompanying drawing in which like numerals indicate like parts throughout the several views, the numeral 5 designates the casing of a conventional tumbler lock. The casing is bored to receive a cylinder 6, which has the customary tumblers 7, only one of which is shown. As is customary, the cylinder is secured against rotation in the casing by the engagement of the tumblers in a groove 8 in the casing, the tumblers being retractable out of the groove upon the insertion of a proper key into a keyway 9 to free the cylinder for 55 rotation.

The front end of the casing 5 is provided with an annular flange 10, the front edge of which is stepped or reduced in diameter as at 11 to form a groove. At one point in its periphery, the groove formed by the stepped portion 11 is gradually increased in depth and width as at 12 to terminate in an enlarged depression or pocket 13. Into this depression or pocket, a lug 14 formed on a cover 15 projects.

The cover 15 is of substantially the same diameter as the flange 10 and covers the exposed front end of the lock to protect the same from the elements.

A spring ring 16, having straight end portions 17 adapted to be received in a bore 18 in the lug 14 of the cover is provided to hingeably mount the cover and also exert spring tension for releasably holding the cover in either closed or open position, as will be hereinafter more fully described.

The major portion of the spring ring 16 lies in a common plane and is received in the groove formed by the portion 11 of reduced diameter. Directly adjacent its end portions, the ring is offset laterally as at 19, so that the end portions are disposed inwardly of the major plane of the ring. The position of the end portions 17 when the ring is free is such that when assembled with the cover and the casing, a spring tension will be exerted on the cover tending to draw the cover towards the casing.

The assembled ring and cover are retained in position on the flange 10 by a stamped sheet metal cap 20. The front face 21 of the cap 20 is apertured to the diameter of the front end of the cylinder and the annular side wall 22 thereof is spun over the back of the flange 10 as at 23 to hold the cap in position. To accommodate the hinged lug 14, the cap has an opening 24.

The spring tension exerted on the cover by the spring ring is utilized to releasably hold the cover in either closed or open position. To obtain this function of the spring ring, the cap 20 has projections 25 at opposite sides of its opening 24, which project forwardly of the plane of the front of the cap and also outwardly beyond its circumference to form a fulcrum about which the spring tension tends to swing the cover.

As shown in Figure 1, the fulcrum afforded by the projections 25 is so positioned with respect to the hinge connection afforded by the end portion 17 of the spring ring that as the cover moves from closed to open position and vice versa, the point of contact between the cover and the fulcrum moves from one side to the other of a

plane passing through the axis of the hinge connection and the center of curvature of the projection 25. In other words, the point of contact moves from one side to the other of dead center, thus enabling the spring tension exerted by the ring to hold the cover in either position.

The slight space between the cover and the adjacent wall of the cap 20, when the cover is in its closed position and which is brought about 10 by reason of the projection of the fulcrum outwardly beyond the front of the cap is not objectionable.

A finger engaging notch 26 is cut into the cover diametrically opposite its hinged mounting 15 to facilitate opening the same.

From the foregoing description taken in connection with the accompanying drawing, it will be readily apparent to those skilled in the art, 20 that this invention affords a simple but very effective mounting for dust covers of key actuated tumbler locks.

What I claim as my invention is:

1. In combination with a key operable tumbler lock having a lock cylinder provided with a 25 key-way, a cover for the front end of the lock, and a single element to hingedly mount the cover for movement to and from closed position about an axis spaced from and angular to the axis of the cylinder and to yieldably hold the 30 cover in either closed or open position, said single element consisting of a wire loop encircling the end of the lock with a part connected with the cover.

2. In combination with a lock and a cover 35 therefor, single means to hingedly mount the cover and exert a spring tension on the cover, said single means consisting of a wire loop encircling the end of the lock with a part connected with the cover, and common means to provide a fulcrum about which the cover swings 40 in response to said spring tension to yieldably hold the cover in closed position and also retain the wire loop assembled with the lock.

3. In combination with a lock and a hinged 45 cover therefor, a fulcrum engageable with the cover, a yieldable hinge pin to mount the cover and cooperate with the fulcrum to yieldably hold the cover in closed or open position, and a cap to hold the yieldable hinge pin assembled with 50 the lock, said fulcrum being part of the cap.

4. In combination with a lock and a cover for

the front end thereof, a wire ring disposed in an annular groove encircling part of the lock with a portion thereof engaged in a bore in a cover part to provide a hinged mounting for the cover.

5. In combination with a lock and a cover for 80 the front end thereof, said cover having a bore in a part thereof, a wire loop encircling part of the lock and having its ends disposed in said bore to hingedly mount the cover, and a cap to hold the wire loop on the lock, said cap carrying 85 means engageable with the cover as a fulcrum about which the cover swings in opening and closing movement.

6. In combination with a lock and a cover 90 therefor, a lug on the cover having a bore, a wire loop encircling part of the lock and having its ends received in said bore to hingedly mount the cover, and a shell engaged over part of the lock to hold the wire loop in place.

7. In combination with a lock comprising a 95 casing and a lock cylinder mounted therein and a cover for the front end of the cylinder, means to hingedly mount the cover comprising, a wire loop disposed in a groove in the casing and having its ends received in a bore in a cover part, and a 100 cap engaged over part of the casing to hold the wire loop in place.

8. In combination with a lock comprising a 105 casing and a lock cylinder therein, a cover for the front end of the cylinder, a wire loop encircling part of the casing and having its ends disposed in a bore formed in a cover part, a cap engaged over the casing to hold the loop in place, and a projection on the cap and cooperating with the resiliency of the wire loop to yieldably hold 110 the cover in either closed or open position.

9. In combination with a lock comprising a 115 casing having a lock cylinder mounted therein, a cover for the lock cylinder front end, a lug on the cover received in a recess formed in the casing, a spring ring encircling the casing and having a part thereof disposed in a bore in said lug, 120 said spring ring exerting a spring tension to draw the cover toward the casing, a cap engaged over the spring ring and part of the casing to hold the ring in position, and means on said cap to form a fulcrum to cooperate with the spring tension of the ring to yieldably retain the cover in either closed or open position.
